FOLDING AUTOMATIC HYDRAULIC JACK

Joseph Halley, Montreal, Quebec, Canada, assignor, by direct and mesne assignments, to Halley's Automatic Hydraulic Jack Syndicate, Montreal, Quebec, Canada

Application March 26, 1937, Serial No. 133,223

3 Claims. (CL 254—93)

This invention relates to hydraulic lifting jacks, particularly for use on vehicles, and of that kind which are operated by fluid under pressure, the fluid first causing the jack to be moved down from a horizontal or out-of-use position into a position for use and then causing the jack to be expanded in order to lift the vehicle. In arrangements of this kind as applied to motor vehicles, a number of jacks may be permanently attached to the chassis or other part of the vehicle so that they may be moved down into vertical positions, and expanded, when desired, a common fluid storage tank being provided with a pump for supplying fluid to the jacks through suitably disposed pipes or conduits.

The object of the present invention is to provide a lifting jack of the above kind of an improved and simple construction, which is efficient and reliable in action.

According to the invention the head of the jack is provided with a fluid admission chamber adapted to turn, with the jack, relatively to a fixed vane or partition against which the fluid reacts to move the jack angularly into a position for use. This fixed vane or partition is preferably carried by a stationary shaft about which the jack is adapted to turn, the fluid being supplied through a passage in the said shaft to the admission chamber. In order that the jack may be extended when it has been moved down into a position for use, the vane or partition is provided with an aperture controlled by a valve which is lifted from its seating at the required moment by a pin or projection extending into the fluid admission chamber, so that the fluid then passes into the interior of the jack and expands the latter. The jack may comprise two telescopic parts adapted to be extended by the fluid, the said parts being returned, when the fluid has been released, by a spring or springs. A spring or springs may also be used to return the jack into its horizontal out-of-use position.

In the accompanying drawings:

Figure 1 is a side elevational view of a hydraulic lifting jack constructed in accordance with this invention, showing the same in its out-of-use position, the dotted lines indicating the position of the jack when brought into a position for use, but before being extended.

Figure 2 is a vertical section through the jack upon a larger scale, when in its out-of-use position.

Figure 3 is a top plan view of the jack partly in section when in its out-of-use position.

Figure 4 is a side elevational view of the jack

in its out-of-use position, showing the side opposite to that which is illustrated in Figure 1, and Figure 5 shows a sectional view through the jack when partly extended.

Referring to the drawings, the improved jack 14, as applied to a motor vehicle, is adapted to be fixed to the chassis of the vehicle, or to any other suitable part, by means of a bracket 15, the latter being adapted to be secured to the vehicle chassis, or other part, by means of an attachment member or plate 16. The bracket 15 is formed with a depending wall 17 having an enlarged portion 18 at one end in which is provided a bearing. Adjacent the said enlarged portion 18 is provided a cross-arm or supporting member 20 which extends horizontally at right angles to the wall 17, the extremity of the said arm extending downwards to provide a support 21 for a stationary shaft 22 about which the jack 14 is adapted to turn.

The jack 14 is composed of two tubular telescopic sections 23 and 24. The inner section 24 is screwed into a base member 26, while the outer section 23, on the other hand, is screwed into a head 25 fixed to a cylindrical casing 35 which is free to turn, with the jack, about the fixed shaft 22. An annular shoulder 27 is provided at the one end of the inner section 24 of the jack, a similar shoulder 28 being attached, such as by a screw, to the opposite end of the outer section 23. The two shoulders lessen friction between the parts and cooperate to prevent the jack sections from pulling too far apart. A packing ring 29 may be provided adjacent the one end of the inner section, while housed within the latter, as shown in Figure 2, is a pair of coiled springs 33 and 34 disposed one within the other, with the ends of the spring 33 engaging stub-shafts 30 and 32, one fixed to the head 25 of the jack and the other carried by a plate 31 fitting within the base or foot portion.

The one-half of the cylindrical casing 35 to which the head 25 of the jack is attached, and which turns about the fixed shaft 22, is occupied at the side nearest the head by a metal block 51 leaving a semi-circular chamber. The fluid for operating the jack is forced by a pump, not shown, through a conduit 56 (Figure 3) into a passage 52 extending axially through the shaft 22 and it enters the said semi-circular chamber 22 in the casing 35 through a radial passage 41 leading from the passage 52. The said shaft 22 carries a fixed paddle, vane, or partition 37 disposed horizontally and dividing the semi-circular fluid admission chamber into two equal compartments

36 and 36^a, as clearly shown in Figure 2 of the drawings. An aperture 38 is formed in said partition and is arranged to be closed by a ball 39, but adapted, when the ball is moved from its seating, to provide a communication between the two compartments 36 and 36^a, so that the fluid may then pass from the compartment 36^a into the compartment 36. A passage 40 extends through the metal block 51 and leads from the compartment 36 to the inside of the inner telescopic part 24 of the jack, while a pin 42 carried by the said block 51 is adapted when the jack and the casing 35 turn through a suitable angle to engage the aperture 38 in the vane or partition and move 10 the ball 39 from its seat.

When the jack is not required for use it is held in a substantially horizontal position alongside the bracket 16 which is attached to the vehicle, in which position it is retained by a pin 42, 20 carried by the base or foot 26 of the inner member of the jack and engaging a notch 43 formed in the edge of the depending part 17 of the bracket. The pin 42 is held securely within the notch by the springs 33 and 34 which normally 25 draw the part 24 of the jack inwards. When, on the other hand, the jack is in a position for use it depends vertically downwards, as indicated by dotted lines in Figure 1, the jack is raised from this position, when the fluid is relieved of the 30 pressure and the foot of the jack is clear of the ground, by means of the springs 48 and 50 which are located within a tubular casing 44 anchored at its one end to the outer part 23 of the jack. The spring 48, which is a tension spring, passes 35 through a central hole in the opposite end of the casing 44, and is disposed within the spring 50 which is of the compression type, the one end of the latter spring bearing against a flange 47 surrounding the central hole through which the spring 48 passes. The outer extremity of the tension spring 48 is anchored to a hook 45 attached to the cross-arm 20 and its inner extremity is attached to a movable plate 49 against which the inner end of the compression spring 45 bears. The arrangement is such that when the jack is moved down into a vertical position, as illustrated in Figure 1, the tension spring 48 is elongated, moving the plate 49 towards the upper part of the casing 44 and thereby compressing the spring 50. Both springs in this 50 manner combine to effect the raising of the jack, when the latter is not required for use.

When it is desired to bring the jack into use the fluid, which may be oil, is forced by the pump 55 (not shown) through the conduit 56 (Figure 3) and enters the axial passage 52 in the fixed shaft 22, being forced into the compartment 36^a through the radial branch passage 41. The fluid fills the said compartment and maintains the ball 38 against its seat. Since the fluid cannot escape it coats with the fixed partition 37 (which fits close up to the wall of the semi-circular chamber) and causes the jack to move down angularly about the shaft 22 towards a vertical 60 position, the pressure of the fluid which effects this turning movement first causing the pin 42 to disengage from the notch 43, the inner part of the jack moving slightly outwards against the restraining action of the springs 33 and 34. 65 When the jack has nearly reached a vertical position the pin 42 enters the aperture 38 and raises the ball 39 from its seat. The fluid now passes through the said aperture into the compartment 70

36 and is forced through the passage 40 into the inside of the inner telescopic part 24 of the jack. This part 24 is now forced downward by the fluid, against the action of the springs 33 and 34, until it reaches the ground, when the outer part 5 23 of the jack rises (since the jack continues to extend) and lifts the vehicle.

When the fluid is relieved of the pressure the weight of the vehicle, assisted by the springs 33 and 34, cause the jack to collapse, the part 24 10 sliding partly within the outer part 23, the collapsing movement being continued after the foot or base 26 of the jack has left the ground by the springs, until the two telescopic parts 23 and 24 lie one within the other. Further, as soon as 15 the base or foot 26 of the jack leaves the ground the jack is moved angularly by the springs 48 and 50 back into its horizontal out-of-use position shown in Figure 1, the pin 42 on the base or foot springing into the retaining recess 43. 20

A separate jack of the above construction may be provided for lifting each wheel of the vehicle, the fluid being supplied by the pump from a common reservoir, and any particular jack being brought into use as occasion requires. 25

The springs 33 and 34 are arranged in substantially the same manner as the springs 48 and 50, the inner spring 34, which is a tension spring being attached at one end to the stub-shaft 30 and at its other end to the stub-shaft 32 which is carried by the plate 31, the latter being loose within the inner part 24 of the jack. The spring 34, on the other hand, is of the compression type, its one end bearing against an internal flange 24^a at the top of the inner part of 35 the jack and at its other end bearing against the plate 31. Thus, when the jack is extended the spring 34 is compressed and the spring 33 tensioned and the two springs cooperate to effect the collapsing of the jack when the fluid is relieved of the pressure. 40

What I claim as my invention is:

1. A hydraulic jack including an outer cylindrical jack section, an inner telescopically engaging jack section, a spring urging the sections 45 into contracted position, a hollow partially cylindrical head carried by the upper end of the outer jack section, and having a port leading into said section, a tubular shaft upon which the head is mounted for rotative movement, a paddle mounted 50 on the shaft, the paddle having a check valve normally preventing passage of motive fluid through the paddle, to the jack sections, means causing the opening of the valve when the head has rotated a predetermined distance to thereby 55 cause the rotation of the jack cylinders from a horizontal to a vertical position and the expansion of the cylinders, and manually controlled means for controlling admission of motive fluid to the cylinders and the release of motive fluid 60 therefrom.

2. A hydraulic jack as set forth in claim 1, characterized by the means for causing the opening movement of the check valve in the paddle comprising a pin carried by said head and movable therewith into engaging and disengaging positions relative to said check valve. 65

3. A hydraulic jack as set forth in claim 1, characterized by spring devices for normally holding the jack in its inoperative elevated position 70 and also acting to aid the aforesaid spring in urging the sections into contracted positions.

JOSEPH HALLEY.
